UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A SPOON.

SPECIFICATION forming part of Design No. 24,507, dated July 30, 1895.

Application filed June 26, 1895. Serial No. 554,141. Term of patent 7 years.

To all whom it may concern:

Be it known that I, CHARLES C. WIENTGE, of the city of Providence, in the county of Providence and State of Rhode Island, have invented and produced a new and original Design for the Handles of Spoons and Similar Articles, of which the following is a specification, reference being had to the accompanying drawings, forming part thereof.

10 Figure 1 represents a handle attached to the bowl portion of a spoon and illustrating my new design, the tine portion of a fork being dotted in position. Fig. 2 represents an enlarged cross-sectional view of the handle, 15 showing the beaded borders and the convex panel.

The leading features of my design for handles of spoons and similar articles consist in the elongated diamond-shaped handle joined 20 to the main portion of the article by a gradually-widening base and having the raised beaded border following the outline and the convex panel included within the border.

In the drawings, 5 indicates the handle, and

6 the bowl portion of a spoon to which the 25 handle is attached. It may, however, indicate the main portion of any similar article, one of which is indicated in dotted lines. The outline of the handle beginning at the main body of the article at 7 7 gradually curves inward, contracting the width of the handle to 8 8, thence outward to 9 9 and again inward to 10. The surface ornamentation consists of the beaded border 11 raised from the obverse surface of the handle and following the outline thereof at a slight distance from the edge. Within the upper portions of the border, 30 above the points 8 8, is the convex panel 12.

What I claim is—

The design for a handle for a spoon or similar article as herein shown and described. 40

In witness whereof I have hereunto set my hand.

CHARLES C. WIENTGE.
